UNITED STATES PATENT OFFICE.

THOMAS E. COLLINS, OF CHICAGO, ILLINOIS.

DOOR-CLOSER.

1,398,317.

Specification of Letters Patent. Patented Nov. 29, 1921.

Application filed December 22, 1919. Serial No. 346,725.

To all whom it may concern:

Be it known that I, THOMAS E. COLLINS, a citizen of the United States, residing at Chicago, in the county of Cook and State of Illinois, have invented certain new and useful Improvements in Door-Closers, of which the following is a specification.

My invention relates to non-liquid door closers, the object being to provide a simple and efficient device of this class with few parts in which the disadvantages inherent in the use of liquid are eliminated. A further object is to provide a device of this class which can be used on right or left hand doors without any modification whatever. A further object is to provide a device of this class with means which positively returns the door to a closed position with automatically operated means for regulating the speed of the power mechanism for returning the door to a closed position.

The above and other features of novelty, advantages and capabilities will become apparent from the detailed description of the accompanying drawings in which I have illustrated such a device embodying one form of my invention.

Figure 1 is a plan view of a door closer embodying one form of my invention, applied.

Fig. 2 is an enlarged sectional view taken on the line 2—2 of Fig. 1.

Fig. 3 is an enlarged sectional view taken on the line 3—3 of Fig. 2.

Fig. 4 is a detailed view of certain of the parts more fully described hereinafter.

Referring to the drawings in detail. The door or swinging member shown in broken lines, is indicated by the numeral (10) and is mounted by means of a hinge (11) on the frame (12).

The construction shown consists generally of a casing having ears or lugs, by means of which the casing is adapted to be mounted on a swinging member, like a door or window, in which casing is mounted a shaft provided with a spring motor adapted to operate the shaft in one direction, which shaft is operatively connected by a flexible belt or cable, to a bracket mounted on the frame adjacent to the swinging member and an expanding brake mounted loosely on the shaft within the casing for regulating the speed of the shaft when operated by the motor.

The casing indicated as a whole by the

reference character (13) is preferably made or cast in two parts, (14) and (15) which parts are connected together by any suitable means as shown. Mounted in alined 60 bearings in the casing is a driven shaft (16) which shaft on one end extends outwardly beyond the casing. Mounted on the outwardly extending end of said shaft is a drum (17) adapted to rotate with the shaft. 65 Wound around said drum and connected at one end thereto, is a flexible cable or belt (18) which flexible belt is connected at its opposite end to a bracket (19), screwed to the frame (12) by any suitable means, such 70 as the screws shown. Mounted on the driven shaft, within the casing and adapted to rotate therewith, by means of a pin, is a sleeve (20) which sleeve has connected to it at one end a coil spring (21) which spring 75 has a comparatively large number of windings around said sleeve with its opposite end connected to a stationary pin (22) extending inwardly from one side of the casing, which spring winding constitutes a 80 spring motor and is adapted to operate the shaft (16) with a comparatively high speed, in one direction, because of the comparatively large number of windings. Adjacent to the spring motor and within the casing 85 there is loosely mounted on the shaft (16) an automatically operated, centrifugally expanding brake. This brake comprises a link (23) loosely mounted on the driven shaft (16) to each end of which link, 90 there is pivotally connected, a swinging shoe (24). Fixed to each shoe is a weighted arm (25). Each shoe is provided with a frictionally engaging surface, preferably of leather. Surrounding the perimeter of 95 the brake shoes on the inside of the casing is a brake drum (26), preferably of leather. Adjacent to the link (23) and within the casing is mounted a ratchet wheel (27) adapted to rotate with the driven shaft 100 (16). Mounted on the link (23) is a spring pressed pawl (28) designed to engage the ratchet (27) and cause the link (23) to rotate when the shaft (16) is driven by the spring motor. It will be noticed that the 105 spring motor is constructed of a comparatively long strip of spring steel,—consequently, making a comparatively large number of windings. This is an important feature, for with this arrangement the driven 110 shaft (16) is rotated at a comparatively high speed which is necessary in order to cause

the expanding, centrifugal brake to function properly, in view of the fact that the brake which is loosely mounted on the same shaft, has a direct drive action therewith by 5 means of the pawl and ratchet arrangement. By this arrangement the device is considerably simplified as the speed increasing gearing is eliminated, thus making the structure less expensive, more durable and utilizes no 10 gear to get out of order.

Having described my invention what I claim is:—

In a door closer the combination of a compact casing comprising two flat cupped 15 shaped members, provided with aligned bearings, a shaft rotatably mounted in said bearings and provided with a spindle on one end thereof, extending beyond the bearings suffi-

ciently to receive a drum or the like, a spring motor having a comparatively large number 20 of windings mounted around said shaft in one portion of said casing, and adapted to operate said shaft in one direction, a centrifugal expanding brake loosely mounted on said shaft in the other portion of said 25 casing and directly adjacent to the spring motor and a pawl and ratchet for directly connecting the brake with the shaft.

In witness whereof, I hereunto subscribe my name to this specification in the presence 30 of two witnesses.

THOMAS E. COLLINS.
